ORNAMENTAL TIE-BACK HOLDER

George W. Dover, Edgewood, R. I., assignor to
Dovercraft Company, Inc., Providence, R. I., a
corporation of Rhode Island

Application January 27, 1932. Serial No. 589,098

2 Claims. (Cl. 85—53)

This invention relates to an improved ornamental tie-back holder device for curtains, draperies and the like, and is adapted to be employed by attaching the same to a portion of the window frame to hold the curtains or draperies in draped position relative to the frame. 5 by means of a fabric strip 4 encircling the curtain and secured to the window frame by a tie-back holder device 5 having an exposed convex face 6 to which is applied a suitable surface ornamentation such as may constitute any desired scene as indicated at 7.

One object of the invention is to provide a device of this character which is of simple construction and capable of being made at a low 10 cost, while at the same time it may be formed and ornamented to display any one of a variety of attractive ornamental designs without changing the physical characteristics of the structure.

Another object of the invention is the 15 vision of a device of this character which may be readily constructed from thin metal plates shaped and assembled in a uniform manner but provided with different surface ornamentations whereby a great variety of attractive designs 20 may be provided from similarly constructed devices of this character by merely changing the design applied thereto through surface ornamentation.

Another object of the invention is the 25 vision of an improved device of this character which may be readily and easily constructed, and which comprises a pair of metal plates having thin peripheries connected together in such a manner as to expose to view a convex surface 30 adapted to receive surface ornamentation of a substantially permanent character and providing means for securing an attaching means to the opposite face of the completed device whereby the device may be secured to a portion of a window frame. 35

Referring to the drawing:—

Fig. 1 is a fragmentary front view of a window frame showing a portion of a curtain or drapery in place thereon and illustrating the 40 appearance and position of one of the hold back devices as secured to the frame for holding the curtain in draped position.

Fig. 2 is a disassembled sectional view of the 45 metal plates forming the device together with the attaching means for attachment to the frame prior to their being connected together to form the completed hold back device, and,

Fig. 3 is a sectional view of the completed tie-back device after the several parts have been 50 connected together.

In the embodiment of the invention illustrated herewith 1 designates a portion of a window frame, and 2 a curtain or drapery arranged in vertical folds 3 adjacent to the side portion of 55 the window frame and held in draped position

by means of a fabric strip 4 encircling the curtain and secured to the window frame by a tie-back holder device 5 having an exposed convex face 6 to which is applied a suitable surface ornamentation such as may constitute any desired scene as indicated at 7.

The tie-back holder device comprises a pair of thin metal plates 8 and 9, the metal plate 8 being provided with a central concavo-convex portion 6 surrounded by a bead 10, and having its peripheral edge 11 drawn out at substantially right angles to the main body portion thereof to fold over the peripheral edge 12 of the plate 9 when the parts are arranged in assembled position.

The metal plate 9 is shaped to provide a central recess 14 upon one side thereof and a flaring portion 16 surrounding the central recess 14 and extending substantially to the periphery 12 thereof.

An attaching member 17 which comprises a pin 18 secured in a head 19 is secured to the metal plate 9 by having the flattened surface of the head 19 spot-welded to the recessed portion of the plate 9 or soldered within the recess 14 formed in that face of the metal plate 9 which is opposite to the metal plate 8 when the parts are in assembled position.

After the attaching member 17 is secured to the plate 9, the metal plate 9 is fitted against the plate 8 with the peripheral edge 12 located inwardly of the outstanding peripheral edge 11 and the edge 11 is then bent closely over the peripheral edge 12 as indicated at 20, to secure the parts together firmly, and hold them securely against separation and against movement relative to each other.

From the above description it will be seen that my improved tie-back holder structure is capable of being constructed readily by shaping the metal 95 plates 8 and 9 to form an exposed convex surface upon one plate and a recessed portion upon the other plate off-set from and looking in the opposite direction from the convex face of the first named plate when the parts are in assembled 100 position, together with an attaching pin secured to the recessed portion of the plate 9 for temporary attachment to a window frame.

The surface ornamentation upon the outer convex surface of the plate 8 may be so arranged 105 thereon as to be surrounded by the bead 10 in the form of a border, and may be of any desired character being applied thereto by stenciling, decalcomania, or the like.

The several parts of the tie-back holder are 110

firmly secured together so as to form a firm and rigid structure whereby the parts are held both against separation and against angular movement relative to each other.

5 It will be seen that by forming the tie-back holder of relatively thin plates having their edges securely connected together, and with the pin member 17 firmly secured in the central recess formed in the plate 9 a relatively light tie-back holder is formed which may be secured to the window frame sufficiently to hold the curtain in place without embedding the pin 18 so deeply within the wood as to render its removal difficult or form unsightly scars in the window frame. By 10 providing surface ornamentation for the exposed convex face of the tie-back holder the device may be made to present any one of a plurality of ornamental designs without the necessity of changing the structure of the holder with every 15 changed design. The use of a concavo-convex plate 8 to receive the design and a plate 9 to receive the pin member 17 makes it possible to employ thin metal stock from which to form the plates 8 and 9, and also prevents any marring 20 or distorting of the plate 8 such as would result in attaching the pin member directly thereto.

What I claim is:—

1. In an ornamental tie-back holder for curtains, a pair of continuous thin metal plates of 25 dished formation shaped to interfit with each other in such a manner as to position the dished

portions of said plates in opposed relation with each other, a peripheral edge portion carried by one of said plates and engaging the peripheral edge portion of the other of said plates to secure the plates firmly together with their dished portions in opposed relation to each other, one of said plates having the outer surface thereof provided with a central inwardly directed portion shaped to provide a surface bottomed socket for receiving a pin head in interfitting relation therewith, and a pin member having a head portion shaped to fit within the inwardly directed portion of said plate, and firmly secured to the surface thereof.
